LIGHTER

John Holtzman, New York, N. Y.

Original application July 11, 1928, Serial No. 291,743. Divided and this application April 13, 1935, Serial No. 16,171. Renewed June 28, 1939

6 Claims. (Cl. 67—4.1)

This invention relates to cigar and cigarette lighters of the pocket or table stand type, wherein a serrated wheel is actuated to abrade a pyrophoric element and thereby throws sparks on to a fuel-fed wick to ignite the wick.

This application is a division of my copending application for patent for Lighters, Serial No. 291,743, filed July 11, 1928.

My invention is designed to provide simple, compact and dependable actuating means for the abrading wheel and contemplates such arrangements and combinations of parts as will meet the severe requirements of practical use and the conditions of quantity production at minimum cost.

The various objects of my invention will appear as the description progresses, and will further be clear from the drawings, wherein,

Fig. 1 is a vertical section of one form of lighter, showing how my invention may be applied to a table lighter.

Fig. 2 is a front view of the lighter mechanism of Fig. 1.

Fig. 3 is a vertical section of a modification showing a simpler form of actuating mechanism and a reaction member adapted to be engaged by the finger of the user for aiding him in depressing the finger piece.

Fig. 4 is a top plan view of the same.

It will be understood that the practical embodiments of my invention may assume various forms which I will describe separately in detail.

As shown in Figs. 1 and 2, the fuel container 50 may be permanently or removably secured to a suitable tray as 51. The wick 52 passes through the wick tube 53 for exposure above the top of the container. Said wick tube is inserted into and carried by a removable closure member 54 which is preferably tapered to conform to the top of the receptacle and is removably inserted therewith. A suitable frame as 55 is carried by the closure member 54, said frame also carrying the spark producing mechanism. The frame has upstanding ears 56 projecting above the top of the receptacle in which ears is pivoted the shaft 57 on which the abrading wheel 58 is mounted. The frame 55 further carries the tube 59 for the pyrophoric element 60, the spring 61 in said tube serving to press said element against the abrading wheel. A screw as 161 maintains the spring 61 in place and closes the bottom of said tube.

The member 62 for carrying the snuffing cap 63 is pivotally mounted on the shaft 57 and is provided with an extension 64. For swinging said member, the link 65 is pivoted thereto as by

means of the pin 66, the lower end of said link being pivoted as at 67 to the finger piece 68. Said finger piece is pivoted near its left end as viewed in Fig. 1 to the extensions 69 of the frame 55, a spring as 70 serving to urge said finger piece toward its uppermost position and thereby normally to maintain the member 62 in wick capping position.

For operatively connecting the member 62 to the abrading wheel 58 when the finger piece 68 is depressed so that said wheel moves only in the proper direction to ignite the wick, the abrading wheel is formed with teeth on one face thereof of which teeth are engaged by a lip or pawl 71 struck out from the material of the member 62 in a manner which is well known and which need not, therefore, be described in detail. It will be understood, however, that any suitable form of clutch or one way drive may be interposed between the member 62 and the abrading wheel, as is well understood in the art. It will further be seen that on removal of the closure member 54, the entire mechanism is removed from the container, the upper end of which is thereby exposed for the insertion of fuel when desired.

In Figs. 3 and 4, I have shown a modification to enable the ready removal of the container 50 from the stand 51 which is in this case provided with a bottom 75 to form a complete unit. A cap-carrying member 62 is pivoted on the shaft 57 for the abrading wheel 58 and carries the wick cap 63 in the same manner as hereinbefore described. Instead of the spring 70, however, I prefer to provide a spring 76 coiled about the shaft 57 and engaging the frame 55 and the member 62 so that said member is urged toward wick capping position by the spring. In order to simplify the construction, a knurled finger wheel 77 is loosely mounted on the pin 178 in the extension 64 of the member 62 whereby depression of the wheel causes rotation of said member. The wheel 58 may be similarly toothed, as described in connection with Figs. 1 and 2 or a suitable clutch as hereinbefore mentioned may be interposed between the member 62 and the abrading wheel. In order, however, to provide a reaction piece adapted to be engaged by a finger of the user so as to enable the user to apply the proper force to the member 77 to rotate the member 62 and thereby, to rotate the abrading wheel, I prefer to attach the curved finger grip 79 to the frame 55 as at 80. The lower end of said finger grip, however, preferably slotted as at 81 so that the headed screw or rivet 82 may

engage the lower end of said finger grip and removably maintain it in place. It will be seen that on the removal of the closure member 54, the entire mechanism together with the finger grip may be removed from the container 50 in the manner hereinbefore described in connection with Figs. 1 and 2. It will further be seen that in the modification just described, the operating mechanism is greatly simplified by reason of the provision of a finger grip to enable the user to put adequate pressure upon the finger wheel 17, and that upon release of the pressure on said wheel, the various parts are automatically returned to their initial positions.

13. It will further be seen that by giving the bottom a cup-shaped form, a space as 83 is provided between the bottom of the container and the tray 51 for the reception of extra or spare pyrophoric elements which are readily accessible when needed.

14. While I have shown and described various preferred embodiments of my invention, I do not wish to be understood as limiting myself thereto but intend to claim my invention as broadly as may be permitted by the state of the prior art and the terms of the appended claims.

I claim:

1. A lighter having in combination, a receptacle, an abrading wheel journalled near the top of said receptacle, a pyrophoric member, means projecting said pyrophoric member upwardly into frictional engagement with said wheel, a wick extending into said receptacle and projecting from the top thereof on one side of the wheel, a finger piece pivotally carried by the receptacle and adapted to be pressed downwardly, a spring tending to force said finger piece upwardly, a snuffer for said wick, said snuffer comprising a pair of side walls in parallel spaced relation, said walls having projections provided with upwardly converging edges extending above the top of the wheel, and a combined top and front wall joining said side walls except at said converging edges, the wheel projecting upwardly beyond said combined top and front wall and means whereby upon pressing said finger piece downwardly, said wheel is rotated by manual pressure to ignite the wick and said snuffer is removed from the wick, said means comprising a substantially upright link provided with an uppermost portion curved to conform to the curvature of the wheel and arranged outwardly thereof and between said projections, a pivot pin passing through said uppermost portion of the link and through the upper end parts of said projections, and a second pivot pin connecting said finger piece at a point spaced inwardly a substantial distance from the movable end thereof to the lower end of the link.

2. A lighter having in combination, a receptacle, an abrading wheel journalled thereon, a pyrophoric member, means projecting said pyrophoric member into engagement with said wheel, a wick projecting from the receptacle adjacent the wheel, a snuffer for the wick, having projections thereon extending above said wheel, said snuffer being pivoted on the same axis as the wheel, a substantially horizontal finger piece pivotally mounted independently of the snuffer, and a substantially vertical link between a point on the finger piece about a third of the length of the finger piece from the free end thereof and the projections of the snuffer to operate the wheel and the snuffer by manual pressure.

3. A lighter having in combination, a receptacle, an abrading wheel journalled about a horizontal axis near the top of said receptacle, a pyrophoric member in contact with said wheel, a wick projecting from said receptacle on one side of the wheel, a substantially horizontal elongated finger piece, said finger piece being pivoted at one end on an axis spaced from and below the axis of said wheel and adapted to have the other end thereof pressed downwardly, a substantially vertical link pivotally connected at its lower end to a point on said finger piece spaced inwardly a substantial distance from said other end and having operative connection with said wheel whereby said wheel is operable by manual pressure to ignite the wick, said operative connection comprising a wick snuffer pivotally connected to the upper end of the link at a point above said wheel and clutch means between the snuffer and the wheel.

4. In a lighter assembly, a frame, an abrading wheel journalled in the upper part of the frame, a tube mounted in said frame, a member of pyrophoric material in the tube spring-pressed against the wheel, a snuffer pivotally mounted at the upper part of the frame on the same axis as the wheel, a fuel container having a wick detachably connected with said frame, a non-deformable spring-impelled lever pivotally mounted at the lower portion of the frame on a pivot in spaced relation to the pivot for the snuffer and having spaced walls, part of the frame being inserted between said walls, and means including a pin arranged in spaced relation to the axis of the snuffer operatively connecting said lever with said snuffer for rocking said snuffer on its pivot on the operation of the lever, said lever being adapted to be pressed manually to remove the snuffer from the wick, and simultaneously rotate the wheel to produce sparks to light the wick.

5. In a lighter assembly, a frame of greater over-all height than its width, an abrading wheel journalled at the upper part of said frame, a tube mounted in the frame, a block of pyrophoric material in said tube spring-pressed against the wheel, a snuffer pivotally mounted in the upper part of the frame on the same axis as the wheel, a fuel container having a wick detachably connected with the frame and a spring-urged rigid member pivotally mounted at the lower part of the frame and having a pivotal connection with the snuffer for rocking said snuffer on its pivot.

6. An operating assembly adapted to be detached as a unit from the casing of a pyrophoric lighter, said operating assembly comprising an abrading wheel, a frame having interconnected front and back walls carrying said wheel, an actuating lever pivoted at one end to said frame, a snuffer-carrying member having interconnected front and back walls pivoted to the frame at a point in upward spaced relation to said one end of the lever, said snuffer-carrying member in its normal position being positioned to extend across the upper part of the frame and in its operated position being arranged with its front and back walls respectively forming extensions of the front and back walls of said frame, means operatively connecting the other end part of the lever to the snuffer member to operate the snuffer member and means including a ratchet connection between the snuffer member and the wheel to operate the wheel.

JOHN HOLTZMAN.
